ARC HEAD OPERATING MECHANISM FOR
SEARCHLIGHTS

William H. Jacobi, Wilkinsburg, Pa., and Irvine A. Yost, Lakewood, Ohio, assignors to Westinghouse Electric & Manufacturing Company, East Pittsburgh, Pa., a corporation of Pennsylvania

Application June 19, 1937, Serial No. 149,157

11 Claims. (Cl. 176—56)

Our invention relates, generally, to arc searchlights and, more particularly, to a mechanism for manipulating the electrodes and electrode holders, or arc head mechanisms as they are sometimes called, of an arc searchlight.

In the operation of arc searchlights, it is common practice to provide a mechanism for controlling the electrodes and to support this mechanism on the outside of the searchlight drum, usually on the underside of the drum. Where auxiliary manual adjusting means are provided, it is very inconvenient to mount said manual means at a point where they are readily accessible to the operator and still may manipulate the control mechanism within the drum. Furthermore, such manual controls are usually so mounted as to move about a horizontal axis each time the drum is moved about its horizontal axis. An object of our invention is to provide a mechanism which shall function to automatically maintain one electrode of an arc searchlight in a predetermined position and to manipulate the other electrode to strike the arc and to thereafter maintain the other electrode in a predetermined relation with respect to the one electrode.

Another object of the invention is to provide a mechanism which shall operate to automatically feed the electrodes of an arc searchlight to an arc and which functions in response to manual control to change the position of either of the electrodes.

A further object of our invention is to provide an electrode positioning control for an arc searchlight which shall be responsive to both automatic and manual operation.

Another object of our invention is to provide a manual control for an electrode of an arc searchlight which shall be manipulated by a control member which extends from the searchlight trunnion and which is substantially concentric with the axis about which the searchlight rotates in the trunnion.

A further object of the invention is to provide an automatic and a manual control for the electrodes of an arc searchlight, the automatic control mechanism being housed in the trunnion head plate of the searchlight drum and rotatable with the drum on its trunnion pivot and the manual controls being concentric of and extending through the trunnion pivot.

Another object of the invention is to provide manual control and adjusting mechanisms for the electrodes of an arc searchlight, the controls and adjusting mechanisms being concentric with the trunnion bearing and being nested so that some

of the controls extend through other of the controls.

These and other objects and advantages of the invention will be apparent from the following description with reference to the accompanying drawings, in which:

Figure 1 is a diagrammatic representation of a system for automatically and manually controlling the electrodes of an arc searchlight in accordance with our invention;

Fig. 2 is an elevation view partly in section showing the manner in which the automatic control is housed within the trunnion head plate and how the manual controls extend through the trunnion head, and

Fig. 3 is a plan view of a portion of a searchlight with some of the parts cut away to show the relations of the trunnion head, trunnion head plate and control means for the electrodes.

In practicing our invention, we provide a means for controlling the position of the negative electrode by the differential motion between a constant speed motor which regularly feeds the positive electrode and a variable speed motor whose speed may be governed by the arc current or voltage. The method of controlling this motor speed is not an essential part of this invention and is not discussed in detail here. Such a system as that disclosed in the copending application of Oren G. Rutemiller, Serial No. 732,685, filed June 27, 1934, might be used for this purpose. The regular feed of the positive electrode may be accomplished by a system which may be the same as that of the copending application of W. R. Farley et al. Serial No. 149,164, filed June 19, 1937, and may comprise a continuously driven constant speed motor driving a mechanism which rotates the positive electrode and which is made to drive the positive electrode forward by an electromagnetic device which is intermittently actuated for predetermined adjustable intervals.

The drive from the constant speed motor to the positive electrode passes through a differential gearing arrangement which may be actuated manually to adjust the positive carbon. There is a similar differential gearing arrangement in the negative electrode drive with manual means for varying the position of the negative electrode.

A manually operated adjusting means is provided for moving the arc head as a unit along the axis of the positive electrode so as to properly position the arc with respect to the reflector.

A manually operated adjustment is provided for varying the intervals of energization of the

electromagnetic positive electrode actuating means.

These differential drives are compactly arranged and housed within the trunnion head plate 5 which extends from the searchlight drum into the trunnion head. The electrical circuit controller for the electromagnetic actuating device for the positive electrode is also housed in the trunnion head plate and is driven by the constantly rotating motor.

The manual controls for these adjusting devices extend through the trunnion bearing and are all coaxial therewith. An operating handle is attached to each of the controls and the controls are nested and telescoped so as to make a very compact concentric arrangement whose axis will not shift when the searchlight drum is rotated about its horizontal trunnion axis.

Referring to Fig. 1, the mechanism 4 shown enclosed in the broken line is the control mechanism for the electrodes of the searchlight and is very similar to that shown in the French patent to Breguet, No. 697,990. This mechanism comprises a motor 5 which drives an actuating mechanism 6 for the positive electrode 55 through a mechanical linkage which includes worm gear 7, worm wheel 8, gears 9 and 10, a differential gear arrangement 11, gears 12, 13, 14 and 15, a linkage including universal joint 16, shaft 72 and universal joint 17 and worm gear 18.

Motor 5 also drives a gear 19 which is a part of a differential gear arrangement 20 and which cooperates with gear 21, which is driven by motor 22 to control the movement of floating differential gears 23 and 24. The differential in the movement between gears 19 and 21 is transmitted by gears 23 and 24 to shaft 25, which drives the feed mechanism 26 for the negative electrode 54 through a mechanical linkage which includes gears 27 and 28, differential gear arrangement 29, gears 30, 31, 32 and 33 and a linkage which includes universal joint 34, shaft 71 and universal joint 35.

Motor 5 is continuously driven at a constant speed and motor 22 is continuously driven at a speed which may vary with the potential between the positive and negative electrodes or the current flowing in the positive and negative electrodes. The operation of such a system is fully explained in the copending application of Oren G. 50 Rutemiller, hereinbefore referred to.

A manual control is provided to supplement the motor driven control of each of the electrodes. For the negative electrode this control comprises a handwheel 36 which actuates a hollow shaft 37 to turn gear 38, which, in turn, causes the rotation of gear 39 of the differential gearing arrangement 29 through gears 40, 41, 42, 43 and 44. It will be readily seen that rotation of handwheel 36 will cause movement of the negative electrode in an advancing or retracting direction, depending upon the direction in which handwheel 36 is turned. Similarly, handwheel 45 controls the movement of the positive electrode through shaft 46, gears 47, 48, 49, 50, 51, 52 and 53.

The positive and negative electrodes 55 and 54 are mounted upon a movable arc head mechanism, or electrode support, 56 which may be moved to change the position of the arc by the rotation of gear 57, which causes screw threads 58 to move arc head mechanism 56. Gear 57 is actuated by handwheel 59 through a linkage which includes control shaft 60, universal joint 61, shaft 62, universal joint 63 and gear 64.

The operating mechanism for the positive electrode may be the same as that disclosed in the

hereinbefore referred to application of Farley et al. and may include an electromagnetic device 65 which intermittently causes advancing of the electrode 55 under control of a circuit which is governed by the contacting device 66. The exact circuits for this control are not shown or described, since they are fully set forth in the above-mentioned application. Variation of the periods of actuation of magnet 65 is secured by movement of contact device 67 laterally along the 10 surface of rotating contactor 66 by means of operating handle 68 which is connected by shaft 69 to the contact device 67. The contact drum 66 is continuously rotated at a constant speed by motor 5 through gear elements 7 and 10. 15

Referring to Fig. 2, there is shown the mechanism 4 supported on the shaft 13 which, in turn, is secured to plate member 74. Plate member 74 is secured to the drum 75 of the searchlight in the inside of the drum to cover the opening 76 in the 20 side of the drum and has the operating shafts for the positive and negative electrodes and the arc head adjusting mechanism extending through it. On the outside of the drum 75 there is secured a trunnion head plate in the form of a 25 housing 77. This housing 77 forms a closure for the opening 76 in the drum 75 and forms a receptacle into which the operating mechanism 4 extends. Trunnion head 78 is supported on trunnion 79 and carries bearing members 80 which 30 provide a support for rotation of the drum about a horizontal axis. The drum is supported for rotation on these bearings by extension 81 on housing 77 which cooperates with bearings 80. The operating shafts 60, 46, 37 and 69 are concentric 35 and extend through the bearing to the outside of the trunnion coaxial with the bearing, so that they may be convenient to an operator standing beside the trunnion.

Referring to Fig. 3, there is shown a plan view 40 of part of a searchlight with some of the parts in section and others broken away to show the relative positions of the parts hereinbefore described. The plate 74 may be removed from the drum 75 by removing screw bolts 82 and 83 and the whole operating mechanism may be removed as a unit with the plate 74 by disconnecting shafts 71, 62 and 72 and removing operating handles 59, 45, 36 and 68. This arrangement facilitates inspection, maintenance and repair of the operating mechanism 4. The mechanism 4 is protected from heat radiation from the arc by a plate 84 which is supported on and spaced from the plate 74 between the arc and plate 74. The mechanism is oiled without removing it from the case 55 through convenient oiling tubes 85 and 86.

It will be seen that we have provided a compact arrangement of the operating elements for the electrodes and the arc head of an arc searchlight, have provided a housing for these operating elements which also serves as the support for the rotation of the drum around a horizontal axis and have made this mechanism readily removable as a unit from this housing and have provided auxiliary control elements readily accessible from the outside of the drum and positioned along the horizontal axis.

In compliance with the requirements of the patent statutes, we have shown and described 70 herein a preferred embodiment of our invention. It is understood, however, that the invention is not limited to the precise construction shown and described. It is capable of modification by one skilled in the art, the embodiments 75

herein shown being merely illustrative of the principles of our invention.

We claim as our invention:

1. In an arc searchlight, a trunnion, a trunnion head compartment on the drum of said searchlight, an end compartment on said trunnion, means mounting said trunnion head compartment for rotation about a horizontal axis in said end compartment and control means for the electrodes of said searchlight mounted in said trunnion head compartment.
2. In an arc searchlight, a trunnion, an end compartment on said trunnion, a trunnion head compartment on the drum of the searchlight, means for mounting said trunnion head compartment for rotation about a horizontal axis in said end compartment, manual control means for the electrodes of said searchlight mounted in said trunnion head compartment, and operating means for said control means extending from said end compartment.
3. In an arc searchlight, a control mechanism for the electrodes of the searchlight, a trunnion having an end compartment, a searchlight drum having an opening in one side thereof, a plate removably mounted on the inside of said drum in a position to cover said opening, a head compartment mounted on the outside of the drum in a position to cover said opening and to form an outwardly extending compartment on said drum, means for mounting said head compartment in said trunnion end compartment to provide a horizontal axis around which the drum may rotate, and means for mounting said electrode control mechanism upon said plate within said head compartment so that said control mechanism may be removed with said plate.
4. In an arc searchlight, an electrode support, an operating mechanism for the electrodes mounted upon the electrode support a control mechanism for said operating mechanism, a trunnion having an end compartment, a searchlight drum having an opening in one side thereof, a plate removably mounted on the inside of said drum in a position to cover said opening, a head compartment on the outside of said drum in a position to cover said opening and to form an outwardly extending compartment on said drum, means for mounting said head compartment in said trunnion end compartment to provide a horizontal axis around which the drum may rotate, means for mounting said electrode control mechanism upon said plate within said head compartment so that said control mechanism may be removed with said plate, and control means extending through said plate from said control mechanism to said operating mechanism.
5. In an arc searchlight, electrode actuating means, a mechanism for controlling the actuation of the electrodes of the searchlight, said mechanism comprising two motors, means including differential gear arrangements for connecting each of said motors to separate ones of said electrode actuating means, manually controlled means acting upon each of said differential gear arrangements for varying the actuation of said electrodes, a trunnion, a housing on the searchlight drum having means for mounting the drum on said trunnion for rotation about a horizontal axis, said controlling mechanism being contained within said housing and actuating means for said manually controlled means extending through said drum mounting means coaxial with said horizontal axis.
6. In an arc searchlight, electrode actuating means, a mechanism for controlling the actuation of the electrodes of the searchlight, said mechanism comprising two motors, means including differential gear arrangements for connecting each of said motors to separate ones of said electrode actuating means, manually controlled means extending through said drum mounting means coaxial with said horizontal axis.
7. In an arc searchlight, electrode actuating means, a mechanism for controlling the actuation of the electrodes of the searchlight, said mechanism comprising two motors, means including differential gear arrangements for connecting each of said motors to separate ones of said electrode actuating means, manually controlled means extending through said drum mounting means coaxial with said horizontal axis, said controlling mechanism being contained within said housing and actuating means for said manually controlled means extending through said drum mounting means coaxial with said horizontal axis, an arc head supporting said electrodes and their respective actuating means and a manually controlled means for changing the position of said arc head, said last named manually controlled means including an actuating means grouped with, and concentric of, said actuating means for said first manually controlled means.
8. In an arc searchlight, electrode actuating means, a mechanism for controlling the actuation of the electrodes of the searchlight, said mechanism comprising two motors, means including differential gear arrangements for connecting each of said motors to separate ones of said electrode actuating means, manually controlled means acting upon each of said differential gear arrangements for varying the actuation of said electrodes, a trunnion, a housing on the searchlight drum having means for mounting the drum on said trunnion for rotation about a horizontal axis, said controlling mechanism being contained within said housing and actuating means for said manually controlled means extending through said drum mounting means coaxial with said horizontal axis, said mechanism for controlling the actuation of one of said electrodes including an electromagnet, an adjustable interrupter for said electromagnet driven by one of said motors and mounted in said housing and manual adjusting means for said interrupter including an actuating means grouped with, and concentric of, said actuating means for said first manually controlled means.
9. In an arc searchlight, electrode actuating means, a mechanism for controlling the actuation of the electrodes of the searchlight, said mechanism comprising two motors, means including differential gear arrangements for connecting each of said motors to separate ones of said electrode actuating means, manually controlled means acting upon each of said differential gear arrangements for varying the actuation of said electrodes, a trunnion, a housing on the searchlight drum having means for mounting the drum on said trunnion for rotation about a horizontal axis, said controlling mechanism being contained within said housing and actuating means for said manually controlled means extending through said drum mounting means coaxial with said horizontal axis, said mechanism for controlling the actuation of one of said electrodes including an electromagnet, an adjustable interrupter for said electromagnet driven by one of said motors and mounted in said housing and manual adjusting means for said interrupter including an actuating means grouped with, and concentric of, said actuating means for said first manually controlled means, the drum side of said housing comprising a removable side.

able cover plate and means for mounting said mechanism on said cover plate.

9. In an arc searchlight having a searchlight drum, an arc head upon which the arcing electrodes are supported in the drum and means for producing a beam, in combination, means for mounting the searchlight drum on an axis which is substantially normal to the normal direction of the beam projected by the searchlight, and means for manually adjusting the position of the arc head as a unit including a control member extending to the outside of the drum along said axis.
10. In an arc searchlight having a searchlight drum, an actuating mechanism for each of its electrodes in the drum and means for producing a beam, in combination, means for mounting the searchlight drum on an axis which is substantially normal to the normal direction of beam projected by the searchlight, and means for

manually controlling the electrode actuating mechanisms comprising a linkage connected to each of the actuating mechanisms and extending to the outside of the drum along said axis.

11. In an arc searchlight having a searchlight drum, means for producing a beam, an actuating mechanism for each of its electrodes in the drum and a mechanism for adjusting the position of the arc head as a unit in the drum, in combination, means for mounting the searchlight drum on an axis which is substantially normal to the normal direction of the beam projected by the searchlight, and means for manually controlling the electrode actuating mechanisms and the arc head adjusting mechanism comprising a linkage connected to each of the mechanisms and extending to the outside of the drum parallel with said axis.

WILLIAM H. JACOBI.
IRVINE A. YOST.
